BURNER

John W. Miller, Lansing, Mich., assignor to Motor
Wheel Corporation, Lansing, Mich., a corpora-
tion of Michigan

Application January 7, 1943, Serial No. 471,542

8 Claims. (Cl. 158—91)

This invention relates to burners and more particularly to burners of the vaporizing pot type.

The principal object of this invention is the provision of a burner from which the products of combustion (including flame) are discharged in a non-vertical direction, as for example, in a horizontal direction. While such a burner has long been desired and various attempts have been made to produce such a burner, all those which have been heretofore made or suggested have involved nothing more than disposing a conventional vertical type of pot burner in a horizontal position. These have not been entirely satisfactory for various reasons including an inability to obtain a satisfactory premixing of the air and oil vapor in advance of combustion.

I have discovered that this and other disadvantages of the prior horizontal burners can be overcome by constructing a burner with the lower part of substantially conventional vertical form and with the upper part turned or bent to a horizontal or any intermediate position. For best results, I have found that certain changes in the size, number and/or disposition of the air inlet openings as compared with the conventional vertical type—are desirable. When such changes are made, the burner of this invention is free from the disadvantages of prior horizontal type burners and is otherwise fully as good and efficient as the conventional vertical type of burner.

For a fuller understanding of the objects, advantages and scope of the invention, reference should now be had to the following description when read in connection with the accompanying drawings, wherein:

Figure 1 is a vertical sectional view of a burner embodying the present invention;

Figure 2 is a side elevational view of the burner shown in Figure 1;

Figure 3 is an end elevational view of the burner shown in Figure 1;

Figure 4 is a top plan view of the burner shown in Figure 1; and

Figure 5 is a perspective view of the burner pot forming a portion of the complete burner shown in the other figures.

The burner herein shown comprises an outer casing 8 sealed from the atmosphere except for the large air intake opening 9 in one side thereof and a discharge opening 10 in the end wall 11. Disposed within the casing 8 is the burner proper 12. Burner 12 comprises: a tubular side wall 13 in the form of a right angle elbow of substantially uniform cross-sectional area; an imperforate bottom wall 14 joined to one end of the side wall 13 in sealed relation therewith; and a wall 15

partially closing the other end of the side wall and joining the side wall to the casing. The wall 15 is connected to burner side wall 13 and to the outer casing 8 in sealed relation.

5 Burner end wall 15 is provided with a discharge opening aligned with casing discharge opening 10 and with which is associated a tubular sleeve 16 extending into the burner proper and being in sealed engagement with end wall 15. Burner end wall 15 is of pan shape having a tubular side wall 15a and a rim portion 15b which is connected to casing end wall 11 as shown. A sleeve construction is associated with the opening 10 of casing end wall 11 comprising a 10 pair of rings 17 and 18 secured to each other in slidably telescopic relation and extending on both sides of casing wall 11 and being secured to the outer surface thereof by means of a flange carried by ring 18. Ring 17 is axially aligned with and substantially larger than sleeve 16, the inner end thereof preferably being spaced from burner end wall 15 as shown for a purpose to be described more fully hereinafter.

20 Referring now particularly to Figures 1 and 5, the burner pot is shown as divided into two sections by a number of imaginary planes represented by the dotted line 19 extending along the longitudinal axis of the burner pot. Due to the formation of the side wall, it will be understood 25 that the upper section of the tubular burner pot is of a substantially greater volume than the lower section. This division of the burner pot into sections is referred to herein because it has been found advantageous, even though not necessarily 30 essential, to provide the upper section with primary air inlet openings 20 of different quantity, size and/or location than the primary air inlet openings 21 in the lower and smaller section.

35 For example, in a burner comprising a tubular side wall 13 of a substantially uniform internal cross-sectional area and having a diameter of approximately eight inches, the disposition of the air inlet openings may be as shown in Figure 1 with the number and size of openings in the two 40 sections as follows:

Row	Upper sec- tion	Lower sec- tion
A	0.113" dia.	0.1405" dia.
B	0.113 dia.	0.1405 dia.
C	0.0785 dia.	0.116 dia.
D	0.0785 dia.	0.116 dia.
E	0.0625 dia.	0.0995 dia.
F	0.0625 dia.	0.0995 dia.
G	0.0700 dia.	0.1065 dia.

55 This arrangement results in the upper section

having a total wall area of 191.6 square inches and provided with 88 primary air inlet openings of a total area of .50822 square inch; and the lower section having a total wall area of 108.1 square inches provided with 70 primary air inlet openings of a total area of .75659 square inch.

While the foregoing specific dimensions are not critical, best results have been obtained where the total number of air inlet openings in the upper section is larger and their total area is smaller than in the lower section. Likewise it has been found desirable to provide air inlet openings of a greater total combined area in that part of the burner located below the plane indicated by line X-X than in the part located above that plane (see Figure 1).

Secondary air is supplied to the burner outside of end wall 15 through a series of secondary air inlet openings 22 formed in the side flange 15a of end wall 15. Secondary air inlet openings 22 are preferably larger than the primary air inlet openings 20 and 21 and relatively more concentrated as shown. It will be observed that the arrangement of walls 15 and 11 together with ring 17 form a sort of expansion chamber for the reception of air from openings 22 whereby its velocity is reduced prior to entering ring 17 adjacent the discharge opening of burner 12 defined by sleeve 16.

Bottom wall 14 of burner 12 is formed to receive liquid fuel (oil) from a supply pipe 23 in a well or depression 24. The supply of fuel to the burner from a source not shown is regulated by a conventional regulating valve 25. It will be observed that well 24 is located substantially centrally of the larger or upper section of the burner pot, thus placing the fuel inlet 180 degrees from the burner outlet. This arrangement has been found to be advantageous.

Provision is made for manually igniting the fuel delivered to the bottom of the burner through means of a lighter tube 26. In order to prevent any leakage of air into the burner 12 through the lighter tube 26, the upper end thereof is provided with a hinged closure 27 adapted to seal the interior of the tube from the atmosphere.

In use the burner of this application will normally be associated with a conventional combustion chamber connected to a chimney or other draft producing device in the usual manner. Air may be supplied to the burner by means of natural draft or by means of a draft producer, such as a blower, associated with the air inlet opening 9 in the side wall of casing 8. In either case, air first enters casing 8 through opening 9 and then passes into burner 12 through primary air inlet openings 20 and 21 and secondary air inlet openings 22.

The operation of this burner is generally similar to the well known operation of burners of the vaporizing pot type and therefore need not be described in detail. It should be pointed out, however, that in the present burner the fuel vapors tend to become concentrated adjacent the lower section of the burner pot 12. Consequently, in addition to the primary air opening arrangement previously referred to, it is desirable to locate the discharge opening of the burner eccentrically of the outlet end thereof as shown. That is to say, the discharge opening defined by sleeve 16 is preferably positioned above center with a major portion located within the upper section. The use of the sleeve 16 and the specific location of the fuel well 24 are also determined in part by this consideration.

It has also been found desirable to have the burner outlet opening so disposed in relation to the imperforate bottom wall 14 that flame located at the outlet opening can "see" at least a portion of the bottom wall surface. This arrangement is believed to facilitate the generation of fuel vapors.

As used in the claims of this application: the term "tubular" is not limited to a cylindrical section but is intended to define other sections such as square, oval, polygonal, etc.; and the terms "circumference" and "circumferential" define the perimeter and perimetrical dimension of all such sections.

15 By the expression "outer one half of the circumference" as used in the claims in connection with the burner side wall is meant that portion of the side wall which is disposed above and to the left of the series of imaginary planes defined by dotted line 19 in Figure 5; and the expression "inner one half of the circumference" as used in the claims in connection with the burner side wall means that portion of the side wall which lies below and to the right of the series of imaginary planes defined by the dotted line 19 in Figure 5.

The scope of the invention is indicated in the appended claims.

I claim:

- 30 1. A burner of the vaporizing pot type comprising a bottom wall adapted to serve as a fuel receptacle, a tubular side wall connected to the bottom wall and extending upwardly and laterally therefrom, the end of said tubular wall remote from the bottom wall being provided with a discharge opening disposed above and laterally of the central portion of the bottom wall, the axis of the end of the tubular wall remote from the bottom wall forming an angle of substantially less than 40 180° with the axis of the end of the tubular wall adjacent the bottom wall, said tubular wall being provided with a plurality of air inlet openings distributed substantially throughout its circumferential and longitudinal extents, the total area 45 of the air inlet openings in that portion of the tubular wall comprising the outer one half of the circumference thereof being less than the total area of the air inlet openings in that portion of the tubular wall comprising the inner one half of the circumference thereof.
- 50 2. A burner as defined in claim 1 wherein fuel is admitted to the burner adjacent the junction of the bottom wall with the portion of the side wall comprising the outer one half of the circumference thereof.
- 55 3. A burner as defined in claim 1 wherein the discharge opening for the burner is substantially smaller than the minimum cross-sectional area of the burner.
- 60 4. A burner as defined in claim 1 wherein means in the form of a plurality of secondary air inlet openings are provided for the admission to the burner of a concentration of air in the zone adjacent the discharge opening.
- 65 5. A burner as defined in claim 1 wherein the major portion of the discharge opening is disposed within the section of the burner defined by the portion of the side wall comprising the outer one half of the circumference thereof.
- 70 6. A burner of the vaporizing pot type comprising a bottom wall adapted to serve as a fuel receptacle, a tubular side wall connected to the bottom wall and extending upwardly and laterally therefrom, the end of said tubular side wall remote from the bottom wall being provided with

a discharge opening disposed above and laterally of the central portion of the bottom wall, said tubular wall being provided with a plurality of air inlet openings distributed substantially throughout its circumferential and longitudinal extents, the average area of the air inlet openings in the portion of the side wall comprising an outer one half of the circumference thereof being less and the total number of air inlet openings being greater than in the portion of the side wall comprising the inner one half of the circumference thereof.

7. A burner of the vaporizing pot type comprising a circumferentially and longitudinally continuous substantially tubular side wall of substantially uniform cross-sectional area, said wall being provided with a plurality of circumferentially and longitudinally spaced primary air inlet openings disposed throughout substantially the entire extent of the side wall, an imperforate bot-

tom wall joined to one end of the side wall and adapted to serve as a fuel receptacle, the axis of the end of the tubular side wall remote from the bottom wall forming an angle of substantially less than 180° with the axis of the end of the tubular wall adjacent the bottom wall, the end of the tubular wall remote from the bottom wall having a discharge opening disposed above and laterally of the central portion of the bottom wall, the portion of the burner defining the perimeter of the discharge opening lying generally in a plane which intersects the plane of the bottom wall, and means for delivering fuel to the burner in regulatable quantities.

15 8. A burner as defined in claim 7 wherein the tubular side wall is formed to provide a straight unobstructed passageway between a portion of the imperforate wall and the discharge opening.
